UNITED STATES PATENT OFFICE.

WILLIAM G. MACLAUGHLIN, OF WALKERVILLE, CANADA

COMPOUND RAILROAD-RAIL.

No. 800,749.

Specification of Letters Patent.

Patented Oct. 3, 1905.

Application filed December 31, 1904. Serial No. 239,113.

To all whom it may concern:

Be it known that I, WILLIAM G. MACLAUGHLIN, a citizen of the United States of America, and a resident of Walkerville, in the county 5 of Essex and Province of Ontario, Dominion of Canada, have invented certain new and useful Improvements in Compound Railroad-Rails, of which the following is a full and clear specification, reference being had to the accompanying drawings, in which—

Figure 1 is a plan view of a single rail with the tread portion broken away to better show the chair or base part of the rail; Fig. 2, a transverse section of the rail complete; and 15 Fig. 3, a perspective view with the tread portion in section, showing more particularly the manner of joining the ends of the chair or base sections.

The object of this invention is to provide a 20 compound rail which shall be exceedingly simple in construction, inexpensive to manufacture and easily assembled, as well as very durable, and which also shall provide for effectively breaking the joints between the sections 25 without employing fish-plates at the joints, as fully hereinafter set forth:

To the accomplishment of this object and such others as may hereinafter appear the invention consists of the parts and combination 30 of parts hereinafter fully described, and particularly pointed out in the appended claim, reference being had to the accompanying drawings, forming a part of this specification, in which the same reference characters designate 35 like parts throughout the several views.

Referring to the drawing by letters, *a* designates the tread-section, the upper or wheel-bearing part of which is constructed on the ordinary lines, but whose depending web portion *b* is slightly tapered toward its lower end. The chair or base of the rail is provided with the usual lateral spike-flanges *c* and with a pair of upward-extending flanges or plates *d*, extending the full length of the rail and forming 45 a groove or recess into which the flange *b* of the tread-section nicely fits. The upper edges of the flanges *d* fit in grooves in the under side of the tread-section. In this way a compound rail is formed which shall be much 50 easier and cheaper to manufacture than the ordinary solid T-rail and which will be stronger than the same.

The tread-section in assembling the rail parts is arranged to span or break the joints 55 of the chair-sections, as shown in Fig. 1, and the chair-sections are joined in the peculiar

manner shown. Each end of each chair-section is cut back or notched vertically, so that one half *e* of its end wall is forward of the other half *e'*, and these parts of the end wall *e* are connected by a longitudinal wall *e*, so that when the sections are joined they will overlap, the transverse lines of the joint extending inward from opposite sides in different vertical planes to the center of the chair-section 65 and being connected by a central longitudinal joint coincident with the abutting walls *e*. The tread-section spans this joint, as shown in Fig. 1, and the connecting-bolts are passed through openings formed in the projecting 70 parts *d* of the chair-section, as well as through the intermediate web or flange *b* of the tread-section. In this way a very solid joint is made which will require no fish-plates to keep the sections of the chair part in alinement, 75 the extensions *d* serving effectually as fish-plates.

A rail constructed in the manner set forth possesses important advantages over the common solid rail, some of which are as follows: 80 The tread-section may be reversed when it becomes cracked or slivered along one edge, thus contributing materially to the life of the rail. Should the tread-section become cracked, it cannot be displaced from the interlocking 85 flanges, thereby reducing the danger of accident to a minimum. The rail will be exceedingly strong, it being made up practically of a series of plates set on edge. Fish-plates at the joints are rendered unnecessary, thereby 90 greatly reducing the cost of laying the rail and increasing its safety. Made up in the manner described the rail is much easier to bend, and the bending may therefore be done at the point where the rail is laid. 95

Another feature lies in the fact that all the sections are closely interlocked and mutually strengthened, thereby making the rail practically continuous, doing away with the usual objectionable joints, and distributing the 100 weight of the train long distances ahead and to the rear. As will be seen, a worn-out tread portion at any point along the track may be readily removed and replaced by a new section without disturbing the chair and without 105 stopping traffic. Costly bonding is done away with, as it is simply necessary to lay the bond-wires across the abutting joints of the chair-sections in the groove therein.

It will be apparent to those skilled in the 110 art that various mechanical embodiments of the invention are possible, and I therefore do

not wish to be limited to the exact arrangement and construction shown.

What I claim, and desire to secure by Letters Patent, is—

5. In a compound continuous rail, a series of solid one-piece chair-sections provided with a pair of upward-extending separated flanges, the abutting ends of said sections being notched and interlocked, each joint comprising end walls $e'e'$ and a central longitudinal wall e running between the upward-extending flanges so as to form projecting parts d which serve as fish-plates, these projecting parts being pro-

vided with bolt-holes, and a series of one-piece tread-sections having a central depending ¹⁵ flange or web fitting in and extending to the bottom of the groove formed between the upward-extending flanges of the chair-sections, substantially as described.

In testimony whereof I hereunto affix my ²⁰ signature, in the presence of two witnesses, this 19th day of December, 1904.

WM. G. MACLAUGHLIN.
